UNITED STATES PATENT OFFICE

2,467,992

COOLING MEANS FOR ENGINE CYLINDERS

James C. Riple, Jr., Milwaukee, Wis., assignor to
Avco Manufacturing Corporation, a corpora-
tion of Delaware

Application August 6, 1945, Serial No. 609,203

5 Claims. (Cl. 257—261)

1

The invention relates to air cooled combustion engines.

In air cooled engines in which the cylinders are arranged in rows or lines, it is desirable to maintain the cylinders in closely spaced relation and to provide cooling-means which does not require an increase of the interspacing between the cylinders. It is also desirable to adequately cool the cylinder-heads in which the combustion chambers are formed as well as the cylinder barrels.

One object of the invention is to provide baffles which coat with the fins of different areas on the cylinder-barrels and cylinder-heads for efficient heat transfer from the cylinder-heads which are subjected to greater heat than the cylinders.

Another object of the invention is to provide improved baffles which form ducts and flues for efficiently cooling the cylinder-heads and the cylinder-barrels.

Other objects of the invention will appear from the detailed description.

The invention consists in the several features hereinafter set forth and more particularly defined by claims at the conclusion hereof.

In the drawings:

Fig. 1 is a side elevation of a pair of cylinders and their baffles viewed from the intake side for air and embodying the invention, parts being shown in section.

Fig. 2 is a perspective view of a pair of baffles for one cylinder.

Fig. 3 is a side elevation of a cylinder and its baffles viewed from the outflow side for air.

Fig. 4 is a side elevation of a pair of baffles provided with means for clamping them around a cylinder.

Fig. 5 is a section taken on line 5—5 of Fig. 1.

Fig. 6 is a section taken on line 6—6 of Fig. 1.

The invention is exemplified with a pair of cylinders, generally designated 10, of an internal combustion engine. The cylinders are arranged in line and it is to be understood that the invention is applicable to engines with any desirable number of cylinders. Each cylinder comprises a barrel 11 in which a piston operates and a cylinder-head 14 on the end of the cylinder and in which the usual combustion chamber is formed. The inlet and exhaust valves are mounted in the cylinder-head outwardly of the combustion chamber. A cap 16 is secured to the outer end of head 14 and usually encloses the valve-operating mechanism, as well understood in the art. The barrel 11 is provided with continuously an-

2

nular circumferential fins 12 for conducting the heat from the barrel, and which are usually formed by cutting continuous grooves in its outer periphery and are relatively thin in cross-section. The head 14 is provided with circumferential fins 15, which are of non-symmetrical contour and are usually integrally cast with the head, and for efficiency are required to conduct more heat from the head produced by the combustion of fuel in the head adjacent the valves.

The invention includes a pair of complementary baffles, generally designated 20, and disposed on diametrically opposite sides of each cylinder, and which are spaced apart to form an inlet passage 15 a for air, and an outlet passage b. The baffles for each cylinder are separated and adapted to form, with the fins 12 on the barrel 11, transverse passages for directing air from the side at which air flows to the cylinder around the barrel to the outlet side, to form, with fins 15 on head 14, transverse passages for directing air from the inlet side around head 14 to the outlet side, and ducts or flues for conducting air from areas around the outside of the baffle-members extending around the fins 12 on the barrel 11, longitudinally of the cylinders to supplementally cool the fins 15 on the cylinder-head 14. The baffles for each cylinder are of similar construction, disposed on opposite sides thereof and their ends are spaced apart to form the longitudinally extending inlet-passage a for air at one side of the cylinder and a longitudinally extending diametrically opposite passage b for the outflow of air. These passages extend longitudinally of the cylinder for the flow of air to all portions to be cooled.

Each baffle comprises a substantially flat side-wall 22 which is adapted to fit between contiguous sides of a pair of in-line cylinders and extends substantially the length of the cylinder-barrel 11 and head 14. Each baffle also comprises an inner arcuate wall 25 which extends longitudinally along the fins 12 on barrel 11 and around a side-portion of the cylinder-barrel and conforms to the outer periphery of fins 12, for directing air circumferentially between said fins from the inlet passage a to the outlet passage b between the baffles. Each wall 25 substantially contacts the fins 12 to direct the air between said fins. Each arcuate wall 25 terminates in a bead 26 at the inlet passage a and is joined at its opposite end at the outlet passage b to a vertical wall 27.

The arcuate wall 25 of each baffle is spaced inwardly from the side-wall 22 of the same baffle

and a bottom-wall 29 extends between walls 22, 25 and 27 to form a transverse duct 28 which has an open end at the side of the cylinder and at one side of the inlet passage a. Each duct 28 receives air from said open end and conducts it around the arcuate wall 25 to the end of the duct 28 at the side of the cylinder where the outlet passage b is located. The end-wall 27 and side-wall 22 of each baffle are extended longitudinally of the cylinder to a top-end wall 30 which extends across the corner of said walls 22, 27 to form a flue 31 which receives air from duct 28. Top-end wall 30 extends between the fins 15 on head 14, which are disposed at the outer end of the zone of said head, which is subjected to the greatest heat, to extend flue 31 for additional cooling of the portion of the head 14 which is subjected to the greatest heat. Air which flows through ducts 28 to flues 31 is confined longitudinally by the corner formed by end-wall 27 and side-wall 22 so it will flow into the spaces between the fins 15 on head 14 and escape therefrom through the outlet passage b. A curved flange 32 on each end-wall 27 is designed to provide the proper exit passageway for the air emerging from the grooves between fins 15, thereby providing for maximum air flow at a given pressure differential.

Each side-wall 22 is secured by a screw 23 to the outer end of the cylinder. If desired, tie bolts 35 between lugs 34 secured on walls 30 of the baffles may be used to secure baffles around the cylinder.

The operation is as follows: air flows through the inlet passage a between the baffles to fins 12 on barrel 11 and then circumferentially around opposite sides of the barrel on the inner side of arcuate walls 25, through the grooves between said fins to the outlet passage b between the baffles. This air cools the barrel. Air also flows from inlet passage a between the side-walls 22 and cylinder-head 14 to fins 15 on head 14 and around and between said fins to the outlet passage b between the baffles. Streams of air also pass into the transverse ducts 28 formed by arcuate walls 25, side-walls 22, bottom wall 29 and end-wall 27 into the flues 31 which communicate with the fins 15 on head 14 and the grooves between said fins. The flues 31 extend longitudinally of the fins 15 on that portion of head 14 which is subjected to the greatest heat from the combustion chambers in the cylinders and terminate at the outer-most fin on said portion of the head. The streams of air passing into flues 31 flow through the spaces between fins 15 to the outlet passage b. In this manner, the ducts 28 and flues 31 supplement the cooling of the portion of head 14 which is subjected to greatest heat for efficient cooling. The flanges 32 provide for the maximum flow of air emerging from the flues 31.

The construction described results in high efficiency in the transfer of heat units from head 14 and barrel 11 of the cylinder, is simple, and fully utilizes the interspace between adjacent cylinders so that it is not necessary to provide an increase of space between the cylinders for the accommodation of the baffles. The baffles are supported entirely from the cylinders, and may be readily applied thereto.

The invention is not to be understood as limited to the details described, since these may be modified within the scope of the appended claims without departing from the spirit and scope of the invention.

Having thus described the invention, what I

claim as new and desire to secure by Letters Patent is:

1. Cooling means for an air-cooled engine having a cylinder including a cylinder-barrel provided with a series of circumferential fins, and a cylinder-head provided with a series of circumferential fins, comprising: a pair of diametrically opposite complementary baffles having between them longitudinal and diametrically opposite inlet and outflow passages for air and extending longitudinally for the flow of air transversely to and from both series of fins; each baffle including an outer side-wall extending longitudinally along the barrel and the head, an inner wall extending circumferentially around a portion of and longitudinally along the barrel, for directing an inner stream of air from the inlet passage around the fins on the barrel to the outlet passage, the outer wall being spaced from the inner wall, for directing air transversely around the inner wall from the inlet passage, and a structure adjacent the outlet passage forming a flue extending longitudinally along the cylinder head which opens to the air on the outer side of the inner wall and for conducting said last named air to fins on the head and thence to the outlet passage.

2. Cooling means for an air-cooled engine having a cylinder including a cylinder-barrel provided with a series of circumferential fins, and a cylinder-head provided with a series of circumferential fins, comprising: a pair of diametrically opposite complementary baffles having between them longitudinal and diametrically opposite inlet and outflow passages for air and extending longitudinally for the flow of air transversely to and from both series of fins; each baffle including an outer side-wall extending longitudinally along the barrel and the head, an arcuate inner wall extending circumferentially around a portion of and longitudinally along the barrel, for directing an inner stream of air from the inlet passage, around the fins on the barrel to the outlet passage, the outer wall being spaced from the inner wall, for directing air transversely around the inner wall from the inlet passage, and a structure adjacent the outlet passage forming a flue extending longitudinally along the cylinder head, which opens to the air on the outer side of the inner wall and for conducting said last named air to fins on the head and thence to the outlet passage.

3. Cooling means for an air-cooled engine having a cylinder including a cylinder-barrel provided with a series of circumferential fins, and a cylinder-head provided with a series of circumferential fins, comprising: a pair of diametrically opposite complementary baffles having between them longitudinal and diametrically opposite inlet and outflow passages for air and extending longitudinally for the flow of air transversely to and from both series of fins; each baffle including a substantially straight outer side-wall extending longitudinally along the barrel and the head, an arcuate inner wall extending circumferentially around a portion of and longitudinally along the barrel, for directing an inner stream of air from the inlet passage, around the fins on the barrel to the outlet passage, the outer wall being spaced from the inner wall for directing air transversely around the inner wall from the inlet passage, and a structure adjacent the outlet passage forming a flue extending longitudinally along the cylinder head, which opens to the air on the outer side of the inner wall, and for conducting air to said last

named fins on the head and thence to the outlet passage.

4. Cooling means for an air-cooled engine having a cylinder including a cylinder-barrel provided with a series of circumferential fins, and a cylinder-head provided with a series of circumferential fins, comprising: a pair of diametrically opposite complemental baffles having between them longitudinal and diametrically opposite inlet and outflow passages for air and extending longitudinally for the flow of air transversely to and from both series of fins; each baffle including an outer side-wall extending longitudinally along the barrel and the head, an inner wall extending circumferentially around a portion of and longitudinally along the barrel, for directing an inner stream of air from the inlet passage around the fins on the barrel to the outlet passage, the outer wall being spaced from the inner wall for directing air transversely around the inner wall from the inlet passage to the outlet passage, and a structure adjacent the outlet passage at one corner of the cylinder, forming a flue extending longitudinally along the cylinder head, which opens to the air on the outer side of the inner wall, and for conducting air to said last named air fins on the head and thence to the outlet passage.

5. Cooling means for an air-cooled engine having a cylinder, including a cylinder barrel provided with a series of circumferential fins, and a cylinder head provided with a series of circumferential fins of greater diameter than the fins on the barrel, comprising: a pair of diametrically opposite complemental baffles having between them

longitudinal and diametrically opposite inlet and outflow passages for air extending for the flow of air transversely to and from both series of fins; each baffle including an outer side-wall extending longitudinally along the barrel and the head, an inner wall extending circumferentially around a portion of and longitudinally along the barrel, for directing an inner stream of air from the inlet passage around the fins on the barrel to the outlet passage, the outer wall being spaced from the inner wall for directing air transversely around the inner wall from the inlet passage to the outlet passage, the outer wall from the inlet passage to the outlet passage, and a structure adjacent the outlet passage, forming a flue extending longitudinally of the cylinder head, which opens to the air on the outer side of the inner wall, for conducting air to fins on the head and thence to the outlet passage.
